WIRE STRETCHER AND SPLICER

Albert D. Lossee, Sumner, Nebr.

Application September 23, 1941, Serial No. 412,044

5 Claims. (Cl. 140—123.5)

This invention relates to a combined wire stretcher or tightener and splicer.

An object of this invention is to provide a device of this kind which can be readily connected with adjacent ends of a pair of wires for pulling the wires together to stretch or tighten the wires, and which may also be used to twist the wire ends about each other to form a splice and secure the ends together.

Another object of this invention is to provide a pair of telescopically arranged split sleeves with means carried by each sleeve for winding a wire thereupon, the winding means also providing a means whereby the sleeves may be rotated one relative to the other in order to splice the wire ends together.

A further object of this invention is to provide a device of this kind which is simple in construction and relatively light in weight, so that it will not get out of order and can be operated by an inexpert mechanic.

To the foregoing objects and others which may hereinafter appear, the invention consists of the novel construction, combination and arrangement of parts as will be more specifically referred to and illustrated in the accompanying drawing, but it is to be understood that changes, variations and modifications may be resorted to which fall within the scope of the invention as claimed.

Figure 1 is a bottom plan partly broken away and in section of a combined stretcher and splicer constructed according to an embodiment of this invention.

Figure 2 is a sectional view taken on the line 2—2 of Figure 1, with the device in normal position,

Figure 3 is a sectional view taken on the line 3—3 of Figure 2, and

Figure 4 is a fragmentary side elevation of one end portion of the device.

Referring to the drawing the numeral 10 designates generally an outer sleeve or tubular body of substantially frusto-conical configuration, and the numeral 11 designates generally an inner sleeve or tubular member of substantially frusto-conical configuration which is telescopically and rotatably mounted within the outer sleeve or tubular member 10. The outer member 10 has the large end 12 thereof projected outwardly of the adjacent large end of the inner member 11, and the inner member 11 has the small end 13 thereof projected outwardly beyond the adjacent small end of the outer member 10.

The outer member 10 is formed with a longitudinal opening 14 extending from end to end

thereof, and the inner member 11 is also formed with a longitudinal opening or split 15 extending from end to end, which opening or split portion 15 is adapted to be disposed in substantial registry with the opening 14 during the insertion or removal of the wires from these two members 10 and 11. The outer member 10 at the large end 12 thereof is formed with a pair of opposed cutouts 16, as shown more clearly in Figure 2, and a winding means generally designated as 17 is rotatably carried by the outer member 10 adjacent the cutout 16 thereof. The winding means 17 includes a winding drum formed of a shaft 18 which is journaled diametrically across the tubular member 10, and the shaft 18 has fixedly mounted thereon a pair of spaced apart annular flanges 19 and 20 forming a drum generally designated as 21 therebetween.

The flange 20 and the shaft 18 have secured thereto an eye or arcuate bar 22 through which one end of a wire 23 is adapted to be threaded. One end of the shaft 18 has a bell crank 24 fixed to or formed integrally therewith which projects laterally from one side to the tubular member 10. The opposite end of the shaft 18 projects through the tubular member 10 and has fixed thereto a ratchet or toothed member 25. A pivoted pawl 26 is mounted on a stationary shaft or pin 27 which is fixed to the tubular member 10 and projects radially outwardly therefrom, so that the pawl 26 will gravitantly engage the teeth of the ratchet 25 and hold the drum 21 against rotation in one direction, while permitting free rotation of the drum 21 in the opposite or winding direction. The cutouts 16 are provided in order to facilitate the securing of the end of the wire 23 in the eye 22.

The inner sleeve or tubular member 11 is held against endwise movement with respect to the outer sleeve or tubular member 10 by means of a split arcuate rib or abutment 28, which may be secured as by welding 29 or other suitable fastening means to the interior of the outer sleeve or tubular member 10 inwardly from the cutout 16. The tapering construction of the two sleeves or tubular members 10 and 11 provides a means whereby these two members are held against endwise movement in one direction, and the rib or abutment 28 provides for holding the inner sleeve or tubular member 11 against endwise movement in the opposite direction with respect to the outer sleeve or tubular member 10.

A second winding means generally designated as 30 is carried by the small or projected end 13 of the inner sleeve or tubular member 11, and is

provided for the purpose of winding a second or oppositely extending wire 31 thereupon. The winding means 30 includes a shaft 32 which is journaled through the small end portion 13 of the inner sleeve 11, and the shaft 32 has fixed to one end thereof a handle 33, the shaft 32 also has fixed thereto a diametrically extending pin 34 which projects outwardly beyond the peripheral surface of the shaft 32 and is disposed interiorly of the sleeve or inner member 11 so as to thereby hold the shaft 11 against the withdrawal from the sleeve or inner member 11. The pin 34 constitutes a stop which limits the endwise movement of the shaft 32 so that the shaft 32 cannot be withdrawn endwise from the inner sleeve 11. When the shaft 32 is positioned as shown in Figure 1 this shaft constitutes a winding drum, and the end 35 thereof opposite from the handle 33 projects outwardly of the peripheral surface of the inner member 11, so that one end of the wire 20 31 may be twisted thereabout and wound on the projected end 35. The small end of the inner member 11 is formed with a cutout or guide 36 as shown more clearly in Figure 4, so as to guide the wire 31 as this wire is being wound about the outer projecting end 35 of the shaft 32. During the insertion or removal of the wire 23 from the interior of the sleeves 10 and 11, the shaft 32 may be moved endwise to the dotted line position of Figure 1, whereby the end 35 of the shaft 32 will be disposed in inwardly spaced relation with respect to the inner surface of the inner member 11.

In the use and operation of this device the wire 23 is adapted to be extended into the interior of the two members 10 and 11 from the small ends thereof, being extended through the two registering openings 14 and 15 and then threaded into the eye 22. The free end of the wire 23 is adapted to be extended underneath the starting convolution of the wire 23, whereupon crank 24 may be rotated for substantially one complete turn in order to firmly hold the wire 23 on the winding drum 21. The second or opposed wire 31 is inserted into the two sleeves 10 and 11 from the opposite or large ends thereof, being extended, as shown in Figure 2, beneath the winding drum 21 and then passed over the top of the shaft 32. If desired, the shaft 32 may be pulled endwise so as to provide a space between the end 35 of the shaft and the adjacent side of the sleeve 11. The end of the wire 31 is then extended about the small end 13 of the inner sleeve 11, being engaged in the guide cutout 36 and then initially wrapped about the extending end 35 of the shaft 32, which at this time is in a position projecting outwardly of the outer surface of the inner sleeve 11. The handle 33 of the winding means 30 may then be rotated to take up the slack in the two wires or, if desired, the winding means 17 may be rotated to take up this slack. After the slack has been taken up and the two wires 23 and 31 stretched or tightened to the desired degree, the handle 33 may be grasped in one hand so as to hold the inner sleeve 11 stationary. The crank 24 may then be used to rotate the outer sleeve 11 with respect to the inner sleeve 11 thereby twisting the two wires 23 and 31 together at a point between the two winding means 17 and 30. The outer sleeve 10 may be given any desired number of turns to form the desired number of twists in the two wires 23 and 31, and then the crank 24 may be held stationary so as to hold the outer sleeve 10 station-

ary. The handle 33 may be then used to rotate the inner sleeve 11 with respect to the outer sleeve 10 in order to provide for additional turns or twists in the two wires 23 and 31.

5 After the desired number of turns have been formed in the two wires 23 and 31, the handle 33 may be rotated to unwind the wound portion of the wire 31 on the extended shaft portion 35. The crank 24 may then be rotated to unwind 10 the wound portion of the wire 23 on the drum 21. The tightened and spliced wires 23 and 31 will then be disposed in substantial alignment on the sides of the winding means 17 and 30 confronting the openings 14 and 15, so that the 15 stretching and splicing device may then be lifted off the spliced wires, and the projected ends of the two wires may either be additionally twisted about each other or may be cut off.

What is claimed is:

1. A combined wire stretcher and splicer comprising a pair of telescopically arranged tubular members rotatable relative to each other and each having a longitudinal opening extending from end to end thereof, a winding means carried by one of said members adjacent an end thereof, and a second winding means carried by the other sleeve at the end thereof opposite from said first winding means, each winding means constituting a means for rotating one tubular member relative to the other to thereby twist a pair of oppositely extending wires about each other between said winding means.

2. A combined wire stretcher and splicer comprising a pair of telescopically arranged tubular members rotatable relative to each other and each having a longitudinal opening extending from end to end thereof, means holding said members against endwise movement relative to each other, an end of each member projecting 35 outwardly of the adjacent end of the other member, and winding means carried by the projecting ends of said members, said winding means also providing means whereby said members may be rotated relative to each other to thereby twist together a pair of oppositely extending wires engaging said winding means.

3. A combined wire stretcher and splicer comprising inner and outer tubular members each formed with a longitudinal opening, said members tapering from one end to the other, the small end of said inner member projecting outwardly of the adjacent small end of said outer member, the large end of said outer member projecting outwardly of the adjacent large end of said inner member, an arcuate rib carried by the inner surface of said outer member for holding said members against endwise movement relative to each other while permitting rotary movement, a winding means rotatably carried by said outer member outwardly of the large end of said inner member, and a second winding means carried by the projecting small end of said inner member.

4. A combined wire stretcher and splicer comprising inner and outer tubular members each formed with a longitudinal opening, said members tapering from one end to the other, the small end of said inner member projecting outwardly of the adjacent small end of said outer member, the large end of said outer member projecting outwardly of the adjacent large end of said inner member, an arcuate rib carried by the inner surface of said outer member for holding said members against endwise movement relative to each other while permitting rotary movement, a winding means rotatably carried by said

outer member outwardly of the large end of said inner member, means carried partly by said outer member and partly by said winding means for selectively holding said winding means against rotation in one direction, and a second winding means carried by the projecting small end of said inner member.

5. A combined wire stretcher and splicer comprising inner and outer tubular members each formed with a longitudinal opening, said members tapering from one end to the other, the small end of said inner member projecting outwardly of the adjacent small end of said outer member, the large end of said outer member projecting outwardly of the adjacent large end of said inner member, an arcuate rib carried by the inner surface of said outer member for holding said members against endwise movement rel-

ative to each other while permitting rotary movement, a winding means rotatably carried by said outer member outwardly of the large end of said inner member, and a second winding means carried by the projecting small end of said inner member, said second winding means including a shaft journaled through said inner member, a handle on one end of said shaft, and a stop pin carried by said shaft inwardly of the opposite end thereof, said shaft being selectively movable endwise in one direction to dispose said opposite end thereof in inwardly spaced relation with respect to the adjacent side of said inner member whereby one wire disposed on the side of said shaft opposite from the opening in said inner member may be inserted or removed from said inner member.
